UNITED STATES PATENT OFFICE.

HENRY J. FAUBEL AND WILLIAM ROACH, OF ALLIANCE, OHIO.

METALLIC TIE AND FASTENER.

1,100,550.

Specification of Letters Patent. Patented June 16, 1914.

Application filed January 27, 1914. Serial No. 814,815.

To all whom it may concern:

Be it known that we, HENRY J. FAUBEL and WILLIAM ROACH, citizens of the United States, residing at Alliance, in the county of Wayne and State of Ohio, have invented new and useful Improvements in Metallic Ties and Fasteners, of which the following is a specification.

The present invention relates to improvements in railway construction, and particularly to ties for the rails and means for securing the rails upon the ties.

In carrying out our invention it is our aim to construct a novel form of rail tie, which will afford a certain desired resiliency to the rails supported thereon and which when positioned will so engage with and be engaged by the roadbed as to effectively overcome all liabilities of tilting or 20 of movement in either a lateral or longitudinal direction.

It is also our purpose to provide a metallic tie which shall embody a trough like structure having integral blocks or enlargements adjacent its end to provide seats for the rails, the sides of the tie being cut to the upper face of the rests and the side walls formed by the said cuts providing shoulders with which the longitudinal edges of the 25 base flanges of the rails are brought into contact, and thus hold the rails against lateral or swinging movement to sustain all of the rails in proper longitudinal alignment and to provide a perfectly straight 30 track throughout.

A still further object of the invention is the construction of a metallic tie having rail receiving blocks or rests and detachable means associated with the rests for locking 35 the rails thereon, and whereby the employment of spikes or bolts or analogous securing elements are entirely dispensed with, and further whereby the meeting ends of two rails may be securely connected and retained upon the tie without the employment of fish plates, angle bars, etc. and without the use of the aforementioned bolts or spikes.

A still further object of the invention is 40 to construct a metallic tie which shall include a base having its underside formed with crossed intersecting ribs providing therebetween pockets for the reception of the roadbed, sides arising from the base, 45 and blocks forming rail seats integrally con-

nected with the base and the sides and which form both spacing and reinforcing members for the elements which constitute the body of the tie, the blocks having longitudinal openings and having notches adjacent the said openings, rail clamps each including a hooked rail base receiving portion and an elongated body portion are employed, the bodies passing through the openings in the blocks and are provided with slots for the reception of the shank or body portions of wedge keys, the said keys including heads which engage with the rails and the shanks being provided with lugs that are adapted to be sprung into locking engagement with the notches in the blocks, the arrangement being such as to permit of the disassociation of the key and clamp should occasion require.

With the above recited objects in view, and others which will appear as the nature of the invention is more fully understood, the improvement resides in the novel construction, combination and operative arrangement of parts set forth in the following specification and falling within the scope of the appended claims.

The essential features of the invention involved in carrying out the objects above indicated, are necessarily susceptible of embodiment in various forms of construction without departing from the scope of the invention, but certain preferred and practical embodiments are exemplified by the accompanying drawings, in which:

Figure 1 is a plan view of a tie constructed in accordance with the present invention illustrating the means for securing rails thereon, Fig. 2 is a detail longitudinal section on the line 2—2 of Fig. 1, Fig. 3 is a transverse sectional view on the line 3—3 of Fig. 1, Fig. 4 is a sectional view similar to Fig. 2 but illustrating the manner of securing an ordinary rail upon the tie, Fig. 5 is a perspective view of the locking key, Fig. 6 is a similar view of the rail clamp, Fig. 7 is a detail bottom plan view of the tie, Fig. 8 is a sectional view similar to Fig. 4 but illustrating a modification, Fig. 9 is a sectional view approximately on the line 9—9 of Fig. 8, one of the rail clamps and one of the locking keys being shown broken away and in section, in order to more clearly illustrate the manner in which the said clamp and key engage with notches in the

5 rail edges, Fig. 10 is a perspective view of the key employed in connection with the structure illustrated in Figs. 8 and 9, Fig. 11 is a perspective view of a tie constructed in accordance with the invention and which is primarily adapted for receiving and connecting the meeting ends of two rails thereon, Fig. 12 is a greatly enlarged sectional view through one of the blocks or rail rests 10 of the tie and illustrating more clearly the manner in which the wedge key engages with both the rail clamp, the rail and block, Fig. 13 is an enlarged detail longitudinal sectional view taken through the lower 15 member of the rail clamp and illustrating the arrangement of the opening therein through which passes the shank or arm of the wedge key, and Fig. 14 is a perspective view of a rail end showing the longitudinal 20 edges of its base flange provided with notches.

Referring now to the drawings in detail, the numeral 1 designates our improved tie broadly. This tie is made of any desired 25 metal best suited for the purpose, the said metal embodying a certain desired amount of resiliency. The tie comprises a trough-like structure, including a horizontally straight base 2 having right angular sides 3. The sides 3 are preferably of a less thickness than the base 2, and the said base, upon its underface, is formed with ribs 4 which are arranged at different angles and which intersect to provide the said underface of 35 the tie with pockets 5 which are disposed throughout the area of the said tie. The ribs 4 have their ends connected with a bead or flange 6 which is formed upon both the sides and ends of the base. The pockets 5 are adapted to receive the earth of the roadbed when the tie is positioned, and are adapted to prevent, or assist in preventing either the longitudinal or lateral movement 40 of the tie after the roadbed has been tamped 45 around the tie.

The tie, at a suitable distance from each of its ends is formed with integral blocks 7, the said blocks being arranged transversely between the sides 3, and, of course, being 50 also connected with the base 2. The blocks terminate in horizontally straight walls a suitable distance below the upper edges of the sides 3, the said sides projecting above the blocks a distance equaling or slightly 55 exceeding the thickness of the base flanges of the rails at the longitudinal edges thereof, and the said blocks are of a width equaling the width of the said base flanges of the rails. The sides 3 are cut-away in a plane 60 flush with the sides of the block, the lower walls of the said cut-away portions being also flush with the upper faces of the block, the end walls provided by the said cut-away 65 portions, forming a tie with shoulders 8 which are adapted to contact with the longi-

tudinal edges of the base flanges B of the rails R, when the said rails are seated upon the blocks. The blocks are provided with transverse, substantially rectangular openings 9, preferably two in number for each 70 of the blocks, and the said side walls of the said blocks below the said openings are formed with notches 10, one of the said notches being preferably arranged upon one of the side faces of each of the blocks. 75

The numeral 11 designates the clamp for the rails R. Each of these clamps comprises a flat rectangular body member 12 having one of its ends formed with a right angular extension 13, the end of which being provided with an inturned angularly arranged lip 14 that is disposed above the body 12. The lips correspond with the angular formation of the base flanges B of the rails R, and the bodies 12 of the said clamps are adapted to be inserted, one, through each of the openings 9 and to project through the opening to the opposite side of the block. The free or projecting end of the body 12 of each of the blocks is provided with an 80 opening 15, the said opening having an inner straight wall 16 which is arranged at a right angle to the longitudinal plane of the body 12 and side walls which are arranged at a right angle to the end wall 16, but the 85 opposite end wall 17 is disposed at a downward angle. 90

The numerals 18 designate the locking keys. Each of the keys is provided with an angular head 19, and a shank 20. Each of the shanks has its inner face straight and provided with an inturned lug 21, while the outer face or edge of the said clamp is inclined or beveled from its lower edge to its connection with the head 19, as indicated 100 by the numeral 22. The distance between the inner edge of the lug 21 and the outer edge 22 of the locking key 18 is equal to the distance between the wall 16 and the lower edge of the wall 17 at the smaller end of the 105 opening 15, and the key is sustained at an angle until the lug 21 is passed through the opening 15 and bears against or frictionally contacts with the side of the block. In this connection it should be stated that the locking key is constructed of some suitable resiliency or spring metal, and it will be apparent that when the key is forced downwardly until its lug 21 is adjacent the notch 10, the said lug will spring into the notch 110 and lock both the key and clamp as well as forcing both the vertical portion 13 and the lip 14 of the clamp into tight engagement with the longitudinal edge and the upper face of the base B of the rail, to one side of 115 the said rail, the opposite side being engaged by the head 19 of the locking key and the portion of its shank adjacent the said head. It will be further apparent that by the employment of such means for sustain- 120 125 130

ing the rails upon the rests or blocks the necessity of the employment of spikes, bolts or analogous securing elements is entirely dispensed with.

5 The improvement is not only designed to support rails of the ordinary class thereon, but also to sustain and lock thereto that class of rails which have their base flanges centrally formed with a depending rib, such 10 a rail being shown in Fig. 2 of the drawings, and designated by the character R', the rib being also indicated by the character r. To accommodate such rails the blocks or 15 rests 7 are provided with central transverse slots or depressions 23 which provide channels for the reception of the rib r, and the rib is formed with openings 24 which register with the openings 9 in the block, the body 12 of each of the clamping members 20 passing through the said openings r, the angular portions or clips 14 engaging with the upper faces of the base flanges of the rail, while the locking key 18 is employed and secured as previously described.

25 If desired, and as shown in Figs. 8, 9 and 14, the rails R may have their longitudinal edges provided with spaced notches 25, and the clamps, at their juncture of their lips 14 and their vertical portions 13 provided 30 with inturned lugs 26 which are adapted to be received within the notches 25 upon one of the sides of the rails, and likewise the locking key 18' at the juncture of its head and shank is formed with an offset portion 35 or lug 27 which is received within the notch upon the opposite side of the rail. Also the lip or clip 14' of the clamp may be elongated, and extend through suitable orifices 28 formed in the web of the rail at the 40 juncture with its base flange (see Figs. 8 and 9). The locking key engages with the rail clamp and with the block or rest in the usual manner, and by such an arrangement it will be noted that the liability of the lateral or swinging or twisting movement of 45 the rail is entirely and effectively overcome.

It will be, of course, apparent that the ties 1 may be of sufficient width to support the meeting ends of two rails thereon, but, 50 in Fig. 11 of the drawings, we have shown a tie especially constructed for supporting and connecting the said meeting ends of two rails. The tie is constructed in a manner substantially similar to that heretofore 55 described, but the blocks or rail rests 7^a and 7^b extend a suitable distance beyond both of the sides of the tie, thus elongating the blocks and affording the same with ample room to receive two meeting rail ends, the 60 said rail ends being indicated by the dotted lines to the left hand side of the said Fig. 11. In this instance the projecting ends of the blocks are provided with the openings 9 and with the notches 10, and the upper face 65 or rail rest proper of the blocks is provided,

at its longitudinal edges, with spaced studs 30 which receive the notches 25 in the rail ends. The rail clamps, indicated by the dotted lines, in the said Fig. 11, are similar to the rail clamps previously described, as 70 are the locking keys which engage with the walls of the openings 15 of the clamps and which have their studs or lugs received within the notches 10. To the right hand side of the said Fig. 11 the block or rail rest 7^b is centrally formed with a longitudinally 75 extending recess or channel 31, the said channel being provided to receive the ribs r when two of the rails R' are to be connected and secured upon the tie. The rails thus connected are not weakened by the employment of openings for the reception of bolts, or analogous devices, and the employment of fish plates, etc., for the ends of the rails are also not necessitated.

80 From the above description, taken in connection with the accompanying drawings, it will be noted that the channeled or trough-like tie provides for the reception of the ballast of the roadbed upon the bottom and between the sides thereof, which, in connection with the pockets 15, in the base of the tie, effectively sustains the said tie upon the roadbed without liability or danger of the same moving in any direction when under 85 the strain of the rolling stock passing thereover; that the arrangement of the pockets formed by the connecting ribs, below the blocks or rail rests, afford these portions of the tie with the desired amount of resiliency, 90 so that breakage of the rails or of the ties is effectively overcome, and in this connection it should be stated that if desired, cushion plates of yieldable material may be arranged upon the blocks or rests, and furthermore, 95 that the simple and effective coöperation of the rail clamps and locking keys provide means which effectively and securely retain the rails upon the tie but whereby the rails may be removed from the tie should occasion 100 require. To remove the rails a suitable instrument, such as a fulcrum pinch bar may be inserted between one of the sides of the blocks and the lower edge of the shank of the locking wedge key, below the lug thereon, it being noted that the said key terminates a suitable distance above the base of the tie, and if desired, and as illustrated in 105 Fig. 12 of the drawings, the block may be provided with a depression or slot 35 which may be partially closed by the said lower portion of the wedge key and which provides ample space for the insertion of the claw end of fulcrum member to assure the ready 110 release of the key. The further advantages 115 and desirable features of the invention will, it is thought, be perfectly apparent to those skilled in the art to which such invention appertains without more detailed description.

Having thus described the invention, what we claim is:

- 5 1. A metal tie including a base and sides, integrally formed blocks arranged between the sides, said blocks comprising each a seat for a rail, said rail having its longitudinal edges notched, the block having longitudinal openings and notches arranged below the openings, a rail clamp, said clamp including 10 a body which is adapted to pass through one of the openings, a vertical extension which is adapted to engage one of the sides of the block and one of the longitudinal edges of the rail, an inclined lip which is adapted to 15 overlie and engage with the base flanges upon one side of the rail, a lug between the lip and vertical extension adapted to be received within one of the notches in the rail, a headed key having a wedge-shaped shank 20 adapted to be passed through an opening in the body of the clamp, said key being formed with a shoulder between its head and shank which is adapted to be inserted within the notch of the rail, the key having 25 a lug, and the said lug adapted to be sprung into engagement with one of the notches to lock the key and clamp upon the block.
2. A tie comprising a base and spaced sides, a block formed with the base and sides 30 and arranged adjacent each of the opposite ends of the tie, said block being formed with longitudinal openings and notches arranged upon its sides below the openings, rail securing means associated with the blocks,

35 said means including a clamp having a body portion longitudinally movable within each of the openings in the block, a vertical member arising from the said base and embracing one of the sides of the block and one of the longitudinal edges of a rail arranged upon 40 the block, an angular member formed with the vertical member and engaging with the upper face of the base flange and with the web of the rail, the body of the clamp having its free end formed with an elongated opening, the outer wall of which being inclined, a headed locking key having a wedge-shaped shank, said shank being formed of resilient metal and being provided with an inturned 45 lug, the inner face of the shank being straight and the outer face being inclined to agree with the shape of the slot, and the portion of the key between the lug equaling the length of the opening at the reduced portion thereof, the said key adapted to be passed through 50 the opening to bring its lug into engagement with the notch in the block and its head into engagement with the base flange of the rail opposite that engaged by the angular member of the clamp.

55 60 In testimony whereof we affix our signatures in presence of two witnesses.

HENRY J. FAUBEL.
WILLIAM ROACH.
